UNITED STATES PATENT OFFICE

JOSEPH L. CASSELL, OF NEW YORK, N. Y., ASSIGNOR, BY MESNE ASSIGNMENTS, TO WIRED RADIO, INC., OF NEW YORK, N. Y., A CORPORATION OF DELAWARE

COMBINATION RADIORECEIVER AND PHONOGRAPH

Application filed July 17, 1929. Serial No. 378,981.

This invention relates to radio broadcast and phonograph systems and particularly to a combination of a radio receiver and phonograph reproducer having circuits in common.

An object of the invention is to utilize an electrical sound amplifier for radio reception and phonograph reproduction without disconnecting either the radio portion or the phonograph portion from the common circuit.

Another object of the invention is to enable the operation of a radio and phonograph combination circuit separately or simultaneously.

A further object of the invention is to enable the operation of an electrical sound amplifier for either radio or phonograph reproduction at its optimum efficiency and without substantial alteration of the electrical constants of either the radio or phonograph circuits during operation.

A feature of the invention is that the combination circuit embodying the invention may be located in a receiver cabinet and operated with the cabinet permanently closed as the connecting circuits from the phonograph reproducer to the common amplifier are always maintained. Furthermore, the effective impedance of the first audio amplifying transformer is substantially constant at all times.

Other features of the invention will be apparent and the apparatus for accomplishing the above objects more fully understood by reference to the following description and accompanying drawings in which:

Figure 1 is a schematic circuit of a combination radio and phonograph reproducing apparatus embodying the invention;

Fig. 2 is a front elevational view of the control switch; and

Fig. 3 is a cross-sectional view of the switch of Fig. 2.

Referring to the circuit of Fig. 1, carrier signaling waves may be received over either antenna 5 or wire circuit 6 according to the setting of switch 4, and impressed upon a radio frequency amplifying stage 8. Certain of these electrical vibrations are transmitted to detector 9 through a coupling transformer

10 according to the adjustment of tuning condenser 11. After detection, the audio frequency waves are impressed on first audio stage 12 through a coupling interstage transformer 13, and then on second audio stage 15 through an interstage transformer 16. The audio frequency variations are changed into acoustic vibrations by a receiver 17.

The filaments of the vacuum tubes are energized in parallel from a battery 19, while the grid biasing potentials for the tubes of audio stages 12 and 15 are obtained from a battery 20. Plate potentials for the vacuum tubes are supplied by a high potential battery 21.

The anodes of the tubes of stages 8, 12 and 15 are connected to the battery 21 through the primary windings of coupling transformers 10 and 16 and the winding of a retardation coil 18, respectively. The anode of the detector tube 9, however, is connected to the battery through the primary winding of transformer 13 in series with the winding of an electromagnetic reproducer 24, the reproducer winding being in parallel with a potentiometer resistance 25 with its adjustable contact 29. An equalizer shunts the electromagnetic reproducer 24, and comprises a serially connected condenser 26 and inductance 27. This equalizer eliminates needle scratch and the effect of mechanical resonance in the reproducer. A turn table 28 is shown associated with the stylus of the electro-magnetic reproducer in the well known manner.

In the circuit shown in Fig. 1, one position of the adjustable contact 29 entirely eliminates the effect of the phonograph reproducing apparatus from the plate circuit of detector tube 9 without severing the connection of this circuit. When this is accomplished, any voltage variations produced in the winding of the pick-up device 24 are short circuited and are not impressed across the primary winding of the interstage transformer 13. It is only required, therefore, to adjust the contact 29 along the resistance 25 to impress on the audio frequency stages 12 and 15 various voltages from the device 24.

A similar volume control in connection with the reception of signals from the an-

tenna 5 and wires 6 is shown as a potentiometer resistance 30 with a contact 31. In one position of contact 31 the impulses across the resistance 30 are entirely eliminated from reception in the receiver 17. The volume from these sources is controlled by the positioning of the contact 31 along the resistance 30.

In operating the combination circuit described above, two volume control knobs which may be combined into a unitary control as shown in Figs. 2 and 3, corresponding to contacts 29 and 31 may effectively disconnect either source of signals and vary the amplitude of their voltages on the input of the amplifier 12. It is unnecessary to break any connection, remove any tubes from their sockets, use special adaptors, or open the cabinet to transfer the reception from any of the three sources shown. Also since the connections are not broken, the interstage transformer 13 may be designed to match the impedance between the reproducer and the audio amplifier input circuit and between the radio portion of the system and the audio amplifier circuit to permit the greatest energy transfer therebetween and the least distortion.

In Figs. 2 and 3 the control dial for the circuit of Fig. 1 is shown having two concentric dial knobs 32 and 33 mounted on shafts 34 and 35, respectively. The knobs are rotatably attached to their respective shafts by set screws 36 and 37 while the shaft 34 is free to rotate within the shaft 35 when the knob 32 is pulled outwardly to disengage it from the knob 33. The knob 32 is adapted to slide outwardly on its shaft 34 within the limits of slot 39 in which is screw 36. These dial knobs operate as one when, in the position shown, pins 38 of dial 32 are inserted in appropriate holes in the dial 33.

Mounted on the end of shaft 34 is contact 31 which travels over resistance 30 under control of knob 32, and mounted on the end of shaft 35 is contact 29 which travels over resistance 25, under control of dial 33. The shafts, resistances and contacts are insulated from one another except as connections are made to them in accordance with the circuit of Fig. 1. Switch 40 shown in Figs. 2 and 3 is the switch 4 of Fig. 1 and permits the amplifying system to receive signaling impulses from either the aerial 5 or wired radio input 6.

In such a unitary control device, the volume of each system may be controlled independently, each system may be made operative and inoperative, and programs may be selected from anyone of three sources, from a single control point. Furthermore, if simultaneous reception from the space or wired radio and from the reproducer is desired, this may be accomplished by a slight pressure at the dial 32 to seat the pins 38 in their respective recesses of the knob 33. When so engaged and

the device manipulated, the volume of one source will be decreased as the other is increased providing a rapid and simultaneous control of two systems. Such control is advantageous when it is desired to receive music over one source and a different type of signals, such as speech over another source when proper blending or fading is to be effected.

Although this invention has been described in one particular embodiment and circuit arrangement, it is to be understood that it is not to be limited except by the scope of the appended claims.

What is claimed is:

1. In combination, a carrier wave receiving circuit and an electro-magnetic reproducing unit, means for controlling the volume of the carrier wave signals, independent means for similarly varying the signals from said reproducer, and means coacting with both said means for simultaneously controlling the volume of the carrier wave signals and the signals from said reproducer in opposite sense.

2. In combination, a phonograph reproducer unit, a carrier wave receiving system including an audio frequency amplifier stage, and means for simultaneously increasing the input to said audio frequency amplifier from one source and decreasing the input to said audio frequency amplifier from another source.

3. A combination in accordance with claim 2 in which said means comprises a compound potentiometer having a plurality of concentric dials and a plurality of separate resistance units.

4. In combination, a phonograph reproducer unit, a carrier wave receiving system including an audio frequency amplifier stage common to said unit and said system, said unit and said system forming two sources of audio frequency waves, and means for independently increasing the input to said audio frequency amplifier from one source and for independently decreasing the input to said audio frequency amplifier from the other source, said means also being adapted to simultaneously increase and decrease the respective inputs to said audio frequency amplifier from said sources.

5. A combination in accordance with claim 4, in which said means comprises a compound potentiometer having a plurality of concentric dials and resistance units adapted to be moved independently of one another.

6. A combination in accordance with claim 4, in which said means comprises a compound potentiometer having a plurality of concentric dials and resistance units adapted to be moved simultaneously.

Signed at Ampere, in the county of Essex and State of New Jersey, this 28th day of June, A. D. 1929.

JOSEPH L. CASSELL.
